CLAIM

The ornamental design for a coaxial cable connector, as shown and described.

DESCRIPTION

FIG. 1 is a perspective view of a coaxial cable connector showing my new design, wherein the interior details thereof shown broken line form are for illustrative purposes only and form no part of the claimed design;

FIG. 2 is a side elevational showing of the coaxial cable connector of FIG. 1.

FIG. 3 is a left end view thereof; wherein the interior details thereof shown broken line form are for illustrative purposes only and form no part of the claimed design; and,

FIG. 4 is a right end view thereof; wherein the interior details thereof shown broken line form are for illustrative purposes only and form no part of the claimed design.

The portion shown in broken lines in the above Figure form no part of the claimed invention.
